BRIDGE

Thomas Maddock, Safford, Ariz.

Application March 4, 1940, Serial No. 322,064

5 Claims. (Cl. 14—18)

The improvement relates to suspension bridges and largely to their stiffening trusses.

The object of the improvement is to reduce the weight and cost of bridges, to reduce deflection in cables and towers, and increase rigidity.

Provision is made to combine expansion, continuity, pre-stressing and also angular deflection in trusses to largely eliminate the stresses resulting from temperature variations.

On suspension bridges the truss acts as a two hinged structure for dead loads and cable temperature deflections, as a continuous structure for live loads and in addition provision is made for truss length variation for temperature and camber changes.

As the length of the truss varies from temperature an expanding mechanism produces angular deflections in the continuous truss to adjust it to the cable deflection. That is when temperature expands the truss longitudinally the mechanism while retaining continuity in the truss, shortens its lower chord faster than its upper chord creating a vertical deflection in the line of the truss approximately equal to the deflection of the cable at the tower caused by temperature, thus eliminating the temperature bending stress in the truss at the tower. On the contrary when the temperature drops and the truss contracts the mechanism tilts the truss upward approximately as the cable deflects upward on contracting. Complete instead of the usual half continuity is secured for the side span truss, i. e., both ends of the side span are continuous.

Figure 1 is an elevation of a portion of the main span, tower, side span and approach span of a suspension bridge.

Figure 2 is a detail of truss members at towers or abutments permitting expansion and angular deflection while retaining continuity.

Figures 3—4—5—6—7—8 are details of mechanical modifications for obtaining same result.

Figure 9 shows a modified method of securing angular deflection at an abutment.

Figure 1 shows cable 11, tower 12, truss 13, piers 14 and 15, stay 20, hangers 33, main span 17, side span 18 and approach span 19.

Figure 2 shows the truss at pier 14 of Figure 1. The truss chords to the left are raised and those to the right are dropped from horizontal alignment and bent lever members 22—24—25 and 27—28—29 inserted in the chords with their long arms connected by a strut-tie 25—27. The joints 21—22—24—25—27—28—29 are pin connected. The truss is supported at 28 by a rocker resting on pier 14. Rollers are likewise used. The ver-

tical member 24—29 maintains the chord alignment. Hangers 33 are shown. The variable counterweights 44 suspended at 26 on the lower lever arm and from the pier 14 is one method of prestressing the mechanism to compensate for the difference in distance between pins 24 and 25 and pins 27 and 28 which difference causes not only angular deflection or rotation of the truss, but also a horizontal thrust in the truss.

Figure 3 differs from Figure 2 in several separate modifications. The lever arms 32—34—35 and 37—38—39 are but slightly bent and their connecting strut-tie 35—37 is reduced in length. The truss chords to the left are increased and those to the right are reduced in vertical distance apart to provide space to insert the lever members. The distance 32—34 equals the distance 38—39 but the distance 34—35 is greater than the distance 37—38 so under truss expansion the inclination of 38—39 is greater than 32—34 causing the lower chord to shorten faster than the upper chord, producing angular deflection in the truss. On the contrary when the truss contracts it is deflected upward in coordination with the cable.

The vertical member 34—38 is not supported on the pier 14 but as modified the truss is carried by the hangers only, to reduce bending moments of the truss at the tower by eliminating the effect of the difference in the temperature variations of tower and hangers, also the lengthening of hangers and shortening of towers under live loads.

No detail is shown in this figure to compensate for the difference in distance 34—35 and 37—38.

Figure 4 shows a modification consisting of two toggle joints 41—42—43 and 47—48—49 in the upper and lower chord of the truss connected by the strut-tie 42—48. The toggle arms 41—42—43—44 are unequal in length to the toggle arms 47—48 and 48—49 thus under temperature variations deflecting the truss in coordination with the cable as related of Figures 2 and 3. The toggle arm 47—48 is extended and a differential counterweight hung at 46. Pins 47 and 49 are supported by roller bearings on pier 14.

Figure 5 shows a modification of two toggle joints in the chords. Toggle arm 2—3 is extended as a lever arm to 4 where it is connected by the strut-tie 54—59 to the elbow of the toggle 59—50. Angular deflection is produced by truss length variation as the distance 52—53 is less than the length of 53—54 and 58—59 in the same manner that truss deflection is coordi-

nated with cable deflection as related of Figures 2 and 3, etc. Toggle arm 58-59 is extended and a differential weight 44 suspended at 56. Pin 58 is supported by a roller bearing on pier 14.

Figure 6 shows a modification in which the chords of the truss are connected by two equally long hangers or supporters 61-62 and 63-64 separated horizontally. Angular deflection is secured by inclining the hangers in opposite directions. For instance as the left and right portions of the truss separate due to temperature contraction in the truss the hanger 63-64 becomes more vertical while the hanger 61-62 becomes more inclined, thus the vertical distance 63-64 is increased while the vertical distance 61-62 decreases, deflecting the truss upwards. The position shown in Figure 6 is for neutral temperature. The length and inclination of the hangers determine the amount of the deflection and its coordination with the cable deflection from temperature. The vertical member 62-65 is supported at pin 65 by a roller bearing.

Figure 7 shows a modification consisting of two toggles 81-82-83 and 88-89-89 inserted in the chords with the elbows of the toggles connected by the strut-tie 82-89. The toggle arm 82-83 is longer than the arm 88-89 so as the truss and cable expand from temperature the distance 88-89 shortens faster than the distance 81-83 and the truss deflection is coordinated to that of the cable. The member 83-88 is shown inclined to compensate or pre-stress the truss against horizontal thrust.

Figure 8 shows a modification in that the truss is connected by an expanding mechanism consisting of a turn-buckle 2 in each chord connected to operate simultaneously by the link belt chain 5 running on the sprocket wheels 3 and 6. Angular deflection is secured by differing the diameters of the sprocket wheels. The sprocket wheel 3 is larger than the wheel 6 so that the turnbuckle 2 in the lower chord revolves faster than the turnbuckle in the upper chord deflecting the truss downward with expansion and upward with contraction in coordination with the deflection in the cable. The pitch of the left and right hand screws on bolts 1 and 4 is regulated to provide frictional resistance to absorb the difference in rotating force produced by the difference in diameter of the sprocket wheel when they are working in opposition but not to resist movement when chords are subject to stress of like direction, i. e., temperature adjustment occurs between the reversal stresses of live loads.

Figure 9 shows a method of securing angular deflection and continuity where there is no approach span or where the stress in the truss chord is relatively small as compared to that in the cable and the pier 15 is relatively short or can sustain horizontal thrust. The cable 11 is attached to the truss 13 and the stay 20 at 111. The truss rotates on pin 112, the deflecting angle depending upon the length and stress in the stay 20.

In using an expanding mechanism on pier 15 the side span 18 is fixed to the pier and the angular rotation of the side span truss is controlled by the length of the approach span or spans 19.

The expanding continuous mechanism shown in Figures 2-3-5-6-7 transmit shear as well as moment and are either suspended or supported by rollers or rockers. The turn-buckle mechanism shown in Figure 8 also is modified to

transmit shear and apply to suspended as well as supported positions. All movable joints in the various figures of trusses are shown by a small circle representing a pin. Other joints may be rigid.

In common practice suspension bridge trusses are designed as two hinged at towers, three hinged at towers and span center, or continuous on main span with side span fixed at tower and supported at abutment. Temperature changes result in large stresses and transfers of dead loads from cables to trusses, etc. This application provides for continuity throughout by providing internal expansion at towers on multiple spans or at towers and abutment piers of spans consisting of main and side spans.

By rotating the trusses to correspond with cable sag, deflections on continuous trusses are increased near towers and thus decreased at center of the span when subject to higher temperatures, also the full weight of the dead load and the strength of the trusses resist the uplift on the cable of an empty span or portion thereof induced by live loads elsewhere.

Likewise at low temperatures the strength of the truss does not increase the cable load.

Essentially the mechanism takes up slack in the cables thus reducing deflection in towers and trusses.

Pre-stressing the truss before connecting hangers or toggles is a substitution for the counterweights shown in some of the drawings, also inclined hangers, springs, reducing gears, etc., are used. No details are shown of slow motion controllers to dampen longitudinal movement when trusses are suspended; also when supported if deceleration, wind, etc., stresses are greater than resistance of roller bearings.

I claim:

1. A suspension bridge comprising a suspension cable; a continuous stiffening truss suspended by hangers from the cable; movable means in the truss connecting adjacent portions of its upper chord and bottom chord, respectively, for permitting opposite longitudinal movement of the portions of each chord as temperature varies; and intermediate means connecting the respective means of the chords and co-ordinating the movement of the means in one chord in relation to the movement of the means in the other chord for producing angular vertical deflection in the truss substantially equal to the deflection produced in the cable by the temperature variation.

2. A suspension bridge comprising a suspension cable; a continuous stiffening truss suspended by hangers from the cable; movable means in the truss connecting adjacent portions of its upper chord and bottom chord, respectively, for permitting opposite longitudinal movement of the portions of each chord as temperature varies; and means co-ordinating the movement of the means in one chord in relation to the movement of the means in the other chord for producing angular vertical deflection in the truss substantially equal to the deflection produced in the cable by temperature variation.

3. A suspension bridge comprising a suspension cable; a continuous stiffening truss suspended by hangers from the cable; movable toggle joints in the truss connecting adjacent portions of its upper and bottom chord, respectively, for permitting opposite longitudinal movement of the portion of each chord as temperature varies; said toggles while being connected to operate simultaneously, having arms of different

length co-ordinating the said longitudinal movement with angular vertical deflection in the truss substantially equal to the deflection produced in the cable by temperature deflections.

4. A suspension bridge comprising a suspension cable; a continuous stiffening truss suspended by hangers from the cable; movable oppositely inclined hangers in the trusses connecting portions of its upper and bottom chords respectively for permitting opposite longitudinal movement of the portions of each chord as temperature varies; and co-ordinating the movement in one chord in relation to the movement in the other chord for producing angular vertical deflection in the truss substantially equal to the deflection produced in the cable by temperature variation.

5. A suspension bridge comprising a suspension cable; a continuous stiffening truss suspended by hangers from the cable; movable turnbuckles in the truss connecting adjacent portions of its upper and bottom chord respectively, for permitting opposite longitudinal movement of the portions of each chord as temperature varies; said turnbuckle being connected with a sprocket chain running over sprockets of different diameter co-ordinating the movement in one chord in relation to the movement in the other chord for producing angular vertical deflection in the truss substantially equal to the deflection produced in the cable by temperature variations.

THOMAS MADDOCK.
